Filed Nov. 23, 1956, Ser. No. 623,848

5 Claims. (Cl. 128—454)

This invention relates to improvements in bathing suits.

The primary object of the invention is to provide a bathing suit incorporating buoyant material which will render a person wearing the garment buoyant even though that person does not know how to swim or has been injured or rendered unconscious so as to be unable to swim.

A further object is to provide a swimming suit incorporating therein cellular plastic material having high properties of buoyancy arranged in such fashion and manner as to be substantially concealed or camouflaged so that the garment has an attractive appearance when worn.

A further object is to provide a garment with buoyant portions formed from flat sheet stock of cellular buoyant material tending to normally maintain a flat shape but so fashioned in the garment as to substantially conform to body contour and to accord with the lines and decor of the garment so as to blend therewith in an attractive manner.

A further object is to provide a buoyant bathing suit which is highly efficient, attractive in appearance, comparatively inexpensive, and which incorporates a high degree of safety to the wearer regardless of the position of the wearer within the water.

Other objects will be apparent from the following specification.

In the drawing:

Fig. 1 is a front view of a bathing suit constituting one embodiment of this invention;

Fig. 2 is a back view of the garment;

Fig. 3 is a sectional view taken on line 3—3 of Fig. 1;

Fig. 4 is a face view of a blank for a part of the suit illustrated in Fig. 3;

Fig. 5 is a detail sectional view taken on line 5—5 of Fig. 1;

Fig. 6 is a fragmentary sectional view taken on line 6—6 of Fig. 2;

Fig. 7 is a fragmentary front view of a garment constituting a modified embodiment of the invention;

Fig. 8 is a fragmentary sectional view taken on line 8—8 of Fig. 4 and illustrating a modified form of the invention;

Fig. 9 is a face view of a part used in another modified embodiment of the invention;

Fig. 10 is a fragmentary front view of another modified embodiment of the invention;

Fig. 11 is an enlarged sectional view taken on line 11—11 of Fig. 10;

Fig. 12 is a fragmentary front view of another modified embodiment of the invention; and

Fig. 13 is a fragmentary rear view of the garment shown in Fig. 12.

Referring to the drawings, and particularly to Figs. 1 to 6, which illustrate one embodiment of the invention, the numeral 10 designates a garment, such as a bathing suit, having a portion 12 adapted to fit around the trunk

2

or torso of the wearer, and leg portions 14. The garment is preferably a woman's garment incorporating therein a brassiere portion 16. The garment may be constructed throughout in a substantially conventional fashion or in any manner found suitable. Thus the back of the garment may be open vertically for a portion of the length thereof, as at the center of the rear thereof, as illustrated in Fig. 2, adequate to accommodate convenient donning and removal of the garment. Suitable fastening means 18, such as a conventional slide fastener, may be employed to secure together the upper parts of the back of the garment as it is worn.

The material of which the garment is formed may be any material which is found suitable, and such material may include elasticized fabric, lining fabric, reinforcing or strengthening fabrics applied at stressed areas, and fabrics having inherent extensibility or elasticity.

Cellular materials are now available upon the market which possess a high degree of buoyancy. Such materials are commonly formed of plastics or synthetic resins, and vinyl type plastics are particularly well suited to cellular internal structure with cells substantially separated so as to provide uniformly dispersed non-communicating individual voids, reducing the specific gravity of the material materially to provide a high degree of buoyancy. One such material which has a high degree of buoyancy is known as "Emsolite" and is the product of the United States Rubber Company. This material is preferred because it is unicellular in nature. Other materials are also available on the market at the present time possessing comparable or lesser but usable properties of buoyancy. Cellular buoyant plastics of this character are commonly produced in sheet form, with one standard sheet being one inch in thickness. The buoyancy of this material is of such order that only a small amount thereof, for example, 120 cubic inches, need be incorporated in a bathing suit to enhance normal body buoyancy sufficiently to render the wearer of the suit safely buoyant in water.

One characteristic of the cellular buoyant sheet material is that it tends normally to maintain its flat form and resists draping by flexing in more than one direction. Consequently, prior attempts to use the material have been limited. To the best of my knowledge, all prior attempts to use the cellular buoyant sheet material in a bathing garment have been unsuccessful because the garments so produced appeared to be excessively bulky and have revealed the use of the cellular material therein. Such appearance characteristics have been unpleasing to the eye, so that prospective purchasers have felt that wearing of the garments would be unflattering and have refused to purchase the garments.

I have found that it is possible to incorporate into a bathing suit an adequate quantity of a cellular buoyant material to provide full and safe buoyancy of the wearer, and at the same time provide attractive and commercially salable styles, when using the material in its normal sheet form. This is to be distinguished from employing cellular buoyant material which is molded to shape designed specially for the intended use and hence is objectionably costly.

I have found that it is possible to employ blocks or sheets of cellular buoyant material in attractive arrangements in a garment. Thus it is possible, for example, to fabricate the brassiere portion of a bathing suit by cutting a blank 20 of said material to a shape of the general character illustrated in Fig. 4. Blank 20 is characterized by a plurality of substantially V cuts 22 extending inwardly from the margin thereof toward the center in a relation to outline a shape having an appearance generally similar to the arrangement and appearance of the petals of certain types of flowers, such as daisies. It will

be understood that the blank will be of generally oval or modified oval form or outline with the outer edges thereof curved. The blank 20 will preferably be skived or otherwise shaped or tapered at its margins, so that the central portion thereof will be substantially of full thickness but the petal portions or segments 24 between the cuts 22 will progressively decrease in thickness toward their outer edges. The shape of the blank will be such that the desired cup shape of a brassiere will be assumed by the blank when the edges of the petal portions 24 separated by the cuts 22 are brought into engagement with each other.

The part 29 is preferably confined between an outer layer of fabric 26 and an inner layer of fabric 28, the same being stitched together, as at 30, around the margin of the member 20 for the purpose of holding the flexed petal parts 24 in substantially continuous edge contact with each other to define the cup-shape desired and substantially as illustrated in Fig. 3. If desired, the member 20 may have a plurality of apertures 32 formed therein to accommodate passage of air and water therethrough for the purpose of overcoming discomfort to the wearer occasioned by reason of the high heat insulating properties of the cellular material.

It will also be understood that the petal members 25 may be completely disconnected and may take the shape of substantially triangular parts, as shown in Fig. 9, which can be assembled in the arrangement illustrated in Fig. 3 by confining the same in proper relation to each other between inner and outer garment layers 26 and 28 suitably stitched together.

The sizes of the two members 20, constituting the brassiere inserts, will normally be insufficient to provide the buoyancy required in the suit, particularly in view of the reduction in the thickness of the margins thereof by skiving required in order to provide the desired contour of the brassiere. I have found that it is possible to increase the quantity of the buoyant material employed in the suit at the brassiere portion thereof by employing strips 34 of the cellular material which are of approximately circular or part-circular cross-sectional shape and which preferably are of a thickness greater than the thickness of the marginal portion of the brassiere-forming insert 20. One or more strips 34 preferably extend completely around each insert or blank portion 20 of the brassiere in the fashion shown in Fig. 3, being anchored in place by the fabric layers 26 and 28 or either thereof and by stitching 35. The marginal strip 34 will preferably have its curved or contoured portion uppermost. It will be understood that the curvature of strip 34 in cross-section need not be part-circular but may be of any cross-sectional contour desired or which will produce a desired or attractive appearance. The use of the strips 34 serves somewhat to camouflage the increased thickness of the brassiere portion of the suit so as to distract attention from the bulged condition resulting from the thickness of the material of which the member 20 is formed, which might otherwise give a padded appearance objectionable because of its unnatural prominence, as compared with the normal brassiere portions of bathing suits.

The provision of a thickened trim strip around a brassiere can also be achieved as seen in Fig. 8, wherein such strip 34' is integral with member 20 and is formed by trimming or skiving a blank 20 or by molding thereof to desired shape and contour.

The appearance of a trim can further be emphasized or carried out by continuing the use of a strip of the cellular material at the top margin of the back of the suit, as at 36. As here illustrated, the strip 36 is of a cross-sectional configuration presenting a curved outer surface, and in cases where the same is applied to a portion of the suit by which only a single thickness of material 38 occurs in the suit, that suiting material may extend completely around the strip 36 to anchor that

strip in place, as by means of stitching 40, as shown in Fig. 6.

It is obviously desirable to incorporate as much of the cellular material in the portion of the unit nearest the head as is possible, so as to cause the body of a person who may be unconscious in the water, to assume a position holding the head above water level. This purpose can be promoted by incorporating within a shoulder strap 42 of the garment a strand 44 of the cellulose material sheathed or enclosed within the fabric 46. The sheath or fabric 46 will preferably be of sufficient strength to sustain the stresses and withstand the stretching action to which a shoulder strap is normally subjected in use. In other words, the sheath 46 will sustain all stresses, or substantially all stresses, thus relieving the cellular insert 44 therefrom and reducing to the greatest extent possible any tendency of the filler material 44 to be compressed so as to reduce the volume of the voids thereof and, consequently, reduce the buoyancy thereof. At the same time the buoyant material is partly positioned at the base of the neck and will serve to impart some buoyancy at a point which will assist in holding above water the head of a person wearing the garment who may be in an unconscious state.

Protection of persons suffering from shock or unconsciousness is a matter of considerable concern by reason of the popularity of the sport of water skiing. This sport entails the hazard of spills while traveling at high speed, with the danger that the skier who falls from his skis may strike the skis, or the water, or obstructions or materials floating on the water in such a way as to become temporarily unconscious or "blacked out" following the fall. The present garment, constructed as described herein, has the buoyant areas thereof so oriented therein as to tend to cause the body of an unconscious wearer to assume the position of greatest protection against drowning, as will be evident.

In the event the shoulder straps 42, or the marginal inserts 36 or 34, or all thereof, are omitted for design purposes or other reasons, or in the event that the total volume or cubage of the buoyant material employed in the inserts 20, 34, 36 and 44 is insufficient to provide the buoyancy necessary for the wearer, it is possible to add sufficient additional buoyant material to provide the required buoyancy, without detracting from the appearance of the garment, by designing the same with projections extending below the brassiere portion of the suit. Such projections can be of attractive design which tends to reduce the prominence of the brassiere portion and to avoid the appearance of objectionable size or bulk. One way in which this can be accomplished is by employing inserts of the cellular buoyant material at 50, projecting below the brassiere portion either directly from the brassiere insert 20 or from the brassiere border 34. The inserts 50 will preferably be positioned symmetrically below each of the brassiere inserts 20 and preferably will be of tapered outline or configuration to be of greatest width at their upper ends and narrowing at the lower ends thereof either to a point or to a desired attractive lower end configuration. It will be understood that the inserts 50 may be skived to provide a cross-sectional configuration which preferably presents a curved transverse appearance thereof when worn, or any other cross-sectional shape deemed attractive. The inserts 50 will be confined within pockets formed in the fabric or other material of which the garment is formed, comparable to the pockets formed to confine the other inserts 20, 34, 36 and 44. The taper of parts 50, lengthwise and in cross-section, can be accomplished by skiving, trimming or shaping flat block material or by molding thereof.

Another form of bathing suit employing a different arrangement of the buoyant cellular material is illustrated in Figs. 10 and 11. In this arrangement a plurality of narrow elongated strips of the buoyant cellular

material are employed in the fabrication of a brassiere portion in a garment 10. Thus, as seen in Fig. 11, the strips 60 may be of any desired cross-sectional configuration, preferably substantially uniform through the length thereof, and these strips will be arranged edge to edge, as seen in Figs. 10 and 11, being held together by or confined within the outer fabric 62 and an inner fabric 64. The two fabrics 62 and 64 are preferably stitched together at 66 between the strips 60, with the stitching extending lengthwise along and between the adjacent edges of the strips 60. As seen in Fig. 10 the strips may vary in width throughout their length as for the purpose of producing a V cut at 68 in the brassiere portion of the suit. The strips 60 will preferably be curved lengthwise to conform to the desired contour of the top edge of the suit, and preferably will continue across the back of the suit, as shown at 61 in Fig. 13. The strips 61 will preferably terminate adjacent the longitudinal center of the suit where the same is separated and provided with a slide fastener 70 or the like in the conventional manner. At points where the strips 60 pass under the arms of the wearer, as shown in cross-section in Fig. 13, the cross-sectional configuration of the strips may vary from that in the front and rear portions of the strips in order to provide a generally tapered upper buoyant insert at 72.

The strips 60 will preferably form only the upper portions of the brassiere cups, and blocks 74 of the buoyant cellular material of desired shape will be incorporated below the lowermost strips 60 to complete the cup when anchored in place or retained by the inner and outer fabric sheath parts 62 and being stitched in place along the stitch lines 76. As seen in Fig. 11, the block 74 will preferably be skived so as to be tapered at its edges or margins to conform to the body contour and also to provide the desired appearance.

The strips 60, 61 being narrow compared to their length accommodate bending or shaping thereof through a wide range of shapes so as to lie in graceful patterns as assembled together, in other words, taking advantage of the linear or strip character of narrow sections of the flexible but normally flat cellular buoyant material, enables a wide range of styling and a wide range of sizes of buoyant material to be incorporated within the garment.

In instances where it is desired to incorporate an amount of the buoyant material in excess of that which is required to produce a brassiere and a rear trim, as above explained, it is possible to incorporate additional strip material in the manner illustrated in Figs. 12 and 13 to the full extent required to provide the greatest amount of buoyancy required for all practical purposes. Thus the strips 78 may be incorporated in the garment 10 retained between inner and outer fabric sheet portions 62 and 64 by stitching between the strips comparable to the stitching 66 as previously explained. In this instance, however, the strips 78 commence at the lower portion of the brassiere and curve downwardly and rearwardly to join the rear trim strips 61. A plurality of strips may be provided, as shown in Figs. 12 and 13, to provide an attractive or decorative appearance and to camouflage the bulk inherent in the use of the cellular buoyant material.

Considerable latitude as to the proportions, dimensions, shapes, contours and configurations of the various parts is possible in the styling of the garment, so that a large number of attractive appearances and styles can be produced. Each of these styles can take advantage of the normally flat sheet character in which the cellular buoyant material is fabricated most economically. The styling and designing of the suit can render it sufficiently attractive in appearance to avoid objection on the score of lack of aesthetic properties which has handicapped the previous attempts of workers in the field to take advantage of the cellular buoyant material to produce a buoyant garment.

While the preferred embodiments of the invention have

been illustrated and described, it will be understood that changes in the construction and in the appearance of the garment may be made within the scope of the appended claims without departing from the spirit of the invention.

I claim:

1. A bathing suit comprising a water pervious sheath of sheet material defining a garment, said sheath having inner and outer layers at the breast portion thereof, and a pair of inserts of cellular non-absorbent buoyant material confined between said layers to define brassiere cups, each cup insert comprising a plurality of portions flexed in one direction only, said layers being stitched together along the edges of said portions to maintain said insert portions in selected flexed shape, each cup defining insert including a plurality of narrow elongated strips arranged side by side with the upper strip following the contour of the top edge of the garment.
2. A bathing suit comprising a water pervious sheath of sheet material defining a garment, said sheath having inner and outer layers at the breast portion thereof, and a pair of inserts of cellular non-absorbent buoyant material confined between said layers to define brassiere cups, each cup insert comprising a plurality of portions flexed in one direction only, said layers being stitched together along the edges of said portions to maintain said insert portions in a selected flexed shape, each cup defining insert including a plurality of elongated strips arranged side by side at the upper part of said cup and a configured part in edge abutment with the lowermost strip and flexed to form the lower part of said cup.
3. A bathing suit comprising a water pervious sheath of sheet material defining a garment, said sheath having inner and outer layers at the breast portion thereof, and a pair of inserts of cellular non-absorbent buoyant material confined between said layers to define brassiere cups, each cup insert comprising a plurality of portions flared in one direction only, said layers being stitched together along the edges of said portions to maintain said insert portions in a selected flexed shape, second buoyant inserts extending across the upper rear portion of said garment, and third buoyant elongated strip inserts arranged side by side and extending from front to back of said garment below said first and second inserts with the ends thereof extending substantially perpendicularly to said first and second inserts.
4. A bathing suit comprising a water pervious sheath of sheet material defining a garment, said sheath having inner and outer layers at the breast portion thereof, and a pair of inserts of cellular non-absorbent buoyant material confined between said layers to define brassiere cups, each cup insert comprising a plurality of portions flexed in one direction only, said layers being stitched together along the edges of said portions to maintain said insert portions in a selected flexed shape, said insert portions constituting pieces of sheet material of uniform thickness.
5. A bathing suit comprising a water pervious sheath of sheet material defining a garment, said sheath having inner and outer layers at the breast portion thereof, and a pair of inserts of cellular non-absorbent buoyant material confined between said layers to define brassiere cups, each cup insert comprising a plurality of portions flexed in one direction only, said layers being stitched together along the edges of said portions to maintain said insert portions in a selected flexed shape, said insert portions being formed from sheet material, some inserts being of different thicknesses at different parts thereof.
